CLAIM

The ornamental design for a skid steer loader vehicle
body, substantially as shown and described.

DESCRIPTION

FIG. 1 is a left front perspective view of a skid steer
loader vehicle body showing our new design;

FIG. 2 is a left rear perspective view thereof;

FIG. 3 is a left side perspective view thereof;

FIG. 4 is a front perspective view thereof;

FIG. 5 is a right side perspective view thereof;

FIG. 6 is a rear perspective view thereof;

FIG. 7 is a left side perspective view thereof with the
boom assembly in raised position;

FIG. 8 is a front perspective view of FIG. 7;

FIG. 9 is a rear perspective view of FIG. 7; and

FIG. 10 is an enlarged top perspective view thereof.

The broken lines in the drawing are for illustrative
purposes only.
